LIQUID DISPENSING DEVICE

Russell C. Taylor, Greenwich, Conn., assignor to
 American Can Company, New York, N. Y., a
 corporation of New Jersey

Application April 29, 1937, Serial No. 139,799

8 Claims. (Cl. 221—23)

The present invention relates to a liquid dispensing device which is adapted to receive a sealed receptacle or can containing a liquid to be dispensed and which it also adapted to receive and hold the liquid from the receptacle, the invention having particular reference to a can opening element which produces a pouring opening in an end of the can and at the same time so mutilates the body of the can that its reuse or its subsequent spurious use as a container for liquids is prevented.

An object of the invention is the provision of a liquid dispensing device having a single opening and mutilating element which operates to produce an opening in an end of a can inserted into the dispenser for draining the can contents into the dispenser and which simultaneously operates to mutilate an adjacent side wall of the can so that the latter cannot be again used as a receptacle for liquids.

Another object is the provision in such a liquid dispensing device of a can opening and mutilating element which is constructed of one piece and formed to shift the can relative to the element when the can is inserted into the dispenser to effect a positive and simultaneous cutting away of at least two adjacent walls of the can so that the can will be destroyed beyond repair for reuse as a container of liquids.

Another object is the provision of a liquid dispensing device having a can opening element of the character described wherein a single pressure applied on an inserted can causes the latter to move vertically down into the dispenser over the opening element thus opening the end of the can and at the same time causes the can to move laterally in the dispenser while mutilating a side wall of its body.

Numerous other objects and advantages of the invention will be apparent as it is better understood from the following description, which, taken in connection with the accompanying drawings, discloses a preferred embodiment thereof.

Referring to the drawings:

Figure 1 is a sectional view of a dispensing device embodying the instant invention, the view showing a can being inserted into the device for opening;

Fig. 2 is an enlarged top plan view of the dispensing device taken substantially along a plane indicated by the line 2—2 in Fig. 1, parts of the device being broken away;

Fig. 3 is a sectional detail of a portion of the upper end of the dispensing device illustrating a

can opening cutter in section and a portion of a can in section showing the position of the can at the completion of an opening operation, the view being taken substantially along the broken line 3—3 in Fig. 2; 5

Fig. 4 is a sectional view similar to Fig. 3 of a part of the upper end of the dispensing device including the cutter and showing the position of a can at the beginning of an opening operation;

Fig. 5 is an elevation of the can opening cutter as viewed substantially along the line 5—5 in Fig. 2; 10

Fig. 6 is a horizontal section of the cutter and a fragment of the dispenser and the can, the view being taken substantially along the line 6—6 in 15 Fig. 3;

Fig. 7 is a side elevation of a fragment of a can adjacent its lower end showing how the can is mutilated by the cutter while opening it; and

Fig. 8 is a section of a lower corner of the 20 can adjacent the mutilation showing also how the bottom of the can is cut through by the cutter during the opening operation, the view being taken substantially along the line 8—8 in Fig. 7.

As a preferred embodiment of the invention 25 the drawings illustrate a device which is adapted to dispense lubricating oil such as used in automobiles. The device mainly comprises a can opening and mutilating element or cutter A (Fig. 1) and a dispenser or cutter supporting member B which is adapted to support the cutter. The dispenser B is also preferably adapted to receive a can C to be opened and to collect and hold the contents of the can after the latter is 30 opened. 35

The dispenser B is similar to dispensers now commonly used in oil and gasoline stations and in garages for dispensing lubricating oil into automobile crank cases and the like. It comprises a cylindrical body 11 (Fig. 1) open at its top end 40 and having an upper outwardly curled or rolled edge 12 extending around the top rim. A similar curled or rolled edge 13 extends around its rim at its lower end.

A bottom 14 is secured within the body 11 and 45 is preferably of an inverted cone shape having a discharge pipe 15 which projects through a side wall of the body. The discharge pipe is connected to one end of a flexible hose or tube 17 having at its opposite end a discharge spout 18 50 for dispensing the contents of the dispenser B. When the discharge spout is in non-discharging position it is supported in an upright position alongside the body wall by a hook 19 which is secured to the curled edge 12 of the body. 55

A handle 21 is provided for carrying the dispenser. This handle is secured by upper and lower rigid straps 22, 23 to a side wall of the dispenser body 11 preferably in a position directly opposite the discharge spout 18 and hose 17.

The cutter A is disposed inside of the dispenser B adjacent its upper open end. It is supported on a side wall of the body 11 preferably adjacent the discharge spout 18 and hose 17. The 10 cutter in cross-section is shaped similar to the letter B having a curved body wall section 25 (Figs. 2, 3, 4, 5 and 6) which is secured by screws 26 to the dispenser body 11.

The ends of cutter body wall section 25 merge 15 into inwardly curved wall sections 27, 28 which meet substantially in a vertical central plane, the traces of which are indicated by a line x—x in Fig. 6. Curved wall sections 27, 28 merge into straight wall sections 29, 31 which are contiguous 20 and parallel. These straight wall sections extend back along the center line above mentioned and toward the body wall section 25.

The upper edges of the curved wall sections 27, 28 are curved upwardly as at 32, 33 (Fig. 5) 25 and are beveled on the inner faces as at 34 (Figs. 3 and 4) to provide sharp cutting edges for the cutter. The upper edge of the straight wall section 29 is curved downwardly as at 36 (Fig. 3) and is preferably beveled off in a sharp cutting 30 edge. The upper edge of the straight wall section 31 is inclined upwardly as a continuation of the edge 33 of wall section 28 and is beveled on its inner face to form a sharp cutting edge 37.

Cutting edge 37 terminates in a sharp spear 35 shaped cutting element 38 which is disposed adjacent the body wall 25. This spear shaped cutting element projects beyond the terminal edge of the straight wall section 31, the latter being cut back or relieved as at 39.

In the can opening operation the spear shaped 40 cutting element 38 of cutter A cooperates with a stationary cam 43 having an inclined cam edge 44. Cam 43 is formed on an inwardly bent upper portion of the curved body wall 25. The cam is directly in line with the straight wall section 31 and extends under the spear shaped cutting element 38 and into the recess 39 with its cam edge 44 in spaced relation to the terminal edge of the straight wall section.

A can to be opened is inserted endwise and in 45 vertical position into the top open end of dispenser B with the bottom of the can resting on the spear shaped cutting element 38 as shown in Fig. 1, the point of the cutting element being disposed adjacent the can end seam. By applying a downward pressure on top of the can the latter is forced down over the cutter.

As the can descends the spear shaped cutting 50 element 38 first punctures the can bottom adjacent its end seam as shown in Fig. 4. Simultaneously with this puncturing action the can end seam engages against and slides along the cam edge 44 of cam 43. This shifts the can sidewise or transversely of the dispenser as the can moves 55 further down over the cutter causing the spear shaped cutting element to also puncture the adjacent vertical side wall of the can. The puncturing of both can bottom and side wall is done almost simultaneously and at the very beginning 60 of the can opening operation.

As the can moves further the sharp upper edge 65 37 of the straight wall section 31 enlarges the puncture openings, producing elongated slits in both can bottom and side wall. The sharp edges 70 32, 33 of the cutter curved wall sections 27, 28

then cut into the can bottom wall severing the latter along a B shaped line 45 (Fig. 6). This produces a large opening 46 in the can bottom through which the contents of the can drains out into the dispenser. The cut away portion of the 5 wall is turned back as at 47 (Fig. 8) to permit rapid draining of the can.

During this opening or can bottom severing 10 operation the sharp upper edge 37 of straight wall section 31 continues to elongate the slit cut into the side wall of the can. This action finally produces a long slot 49 (Figs. 3, 7 and 8) which irreparably mutilates and destroys the can body for 15 subsequent use as a container of liquids.

The can comes to rest with its lower seam seated 20 against the bottom walls of notches 51 which are provided in the upper edges of the curved wall sections 27, 28. The seam also seats against a right angle stop 52 which is secured by a screw 25 53 to the dispenser body 11 on a wall opposite the wall on which the cutter is mounted. This lowermost position is shown in Fig. 3 and in dotted lines in Fig. 1. When the liquid is fully drained from the can into the dispenser it may be poured out in the usual manner through the dispenser discharge 30 hose 17 and spout 18.

It is thought that the invention and many of its attendant advantages will be understood from the foregoing description, and it will be apparent that various changes may be made in the form, 35 construction and arrangement of the parts without departing from the spirit and scope of the invention or sacrificing all of its material advantages, the form hereinbefore described being merely a preferred embodiment thereof.

I claim:

1. A liquid dispensing device, comprising in combination, a dispenser adapted to receive a sealed receptacle containing a liquid to be dispensed and also adapted to receive and hold the liquid from said receptacle, and a stationary cutter secured to an inside wall of said dispenser and having a cutting edge for cutting into the bottom of said receptacle and for substantially simultaneously cutting into an adjacent side wall there- 45 of when the receptacle is inserted into the dispenser and forced down on said stationary cutter to provide an opening in the bottom wall through which the liquid flows into the said dispenser and to mutilate the adjacent side wall of the receptacle 50 so that the latter cannot be used again as a container for liquids.

2. A liquid dispensing device, comprising in combination, a dispenser member adapted to receive a sealed receptacle containing a liquid to be dispensed and also adapted to receive and hold the liquid from said receptacle, a stationary cutter member rigidly secured to an inside wall of said dispenser member and having a cutting edge for cutting into the bottom of said receptacle when the receptacle is inserted into the dispenser member and forced down on said stationary cutter to provide an opening in the bottom wall through which the liquid flows into the said dispenser member, and means on one of said members for shifting the receptacle as it is pushed down on said cutter member to force the cutting edge into and thereby to mutilate a side wall of said receptacle so that the latter cannot be used again as a container for liquids.

3. A liquid dispensing device, comprising in combination, a dispenser adapted to receive a sealed receptacle containing a liquid to be dispensed and also adapted to receive and hold the liquid from said receptacle, a stationary cutter 75

rigidly secured to an inside wall of said dispenser and having a cutting edge for cutting into the bottom of said receptacle when the latter is inserted into the dispenser and forced down on said stationary cutter to provide an opening in the bottom wall through which the liquid flows into the said dispenser, and a cam on said cutter for shifting the receptacle transversely of said dispenser as the receptacle is pushed down on said cutter to force the cutting edge into and thereby to mutilate a side wall of said receptacle so that the latter cannot be used again as a container for liquids.

4. A liquid dispensing device, comprising in combination, a dispenser adapted to receive a sealed receptacle containing a liquid to be dispensed and also adapted to receive and hold the liquid from said receptacle, and a stationary cutter rigidly secured to an inside wall of said dispenser and having a cutting edge for cutting into the bottom of said receptacle and for substantially simultaneously cutting into an adjacent side wall thereof when the receptacle is inserted into the dispenser and forced down on said stationary cutter to provide an opening in the bottom wall through which the liquid flows into the said dispenser and to mutilate the adjacent side wall of the receptacle so that the latter cannot be used again as a container for liquids, said cutter also having a supporting wall for limiting the downward movement of the receptacle.

5. A liquid dispensing device, comprising in combination, a dispenser having a liquid-containing bottom and a dispensing spout on one side, said dispenser being adapted to receive and support a sealed receptacle containing a liquid to be dispensed and also adapted to receive and hold the liquid from said receptacle, a stationary cutter secured to an inside wall of said dispenser on the same side as said dispensing spout and having a cutting edge for cutting into the bottom of said receptacle and for simultaneously cutting into an adjacent side wall thereof when the receptacle is inserted into the dispenser and forced down on said stationary cutter to provide an opening in the bottom wall through which the liquid flows into the said dispenser and to mutilate the adjacent side wall of the receptacle so that the latter cannot be used again as a container for liquids, and means for dispensing said liquid from said dispenser and through said spout while the receptacle is held therein.

6. A liquid dispensing device, comprising in combination, a dispenser adapted to receive a sealed receptacle containing a liquid to be dispensed and also adapted to receive and hold the liquid from said receptacle, a B shaped cutter

having a curved body wall secured to an inside wall of said dispenser and having a middle straight wall including a cutting edge terminating in a spear shaped cutting element for cutting into the bottom of said receptacle when the latter is inserted into the dispenser and forced down on the cutter, said cutter also having curved side walls with cutting edges connecting with said body wall and said middle wall for enlarging the opening made in the bottom wall of the receptacle and for turning back the cut away portions of said bottom wall to provide for rapid draining of the liquid from the receptacle into the dispenser, a cam formed on the body wall of said cutter for shifting the receptacle laterally of the cutter as it is pushed down on the cutter to force the middle cutting edge into a wall adjacent the bottom wall of said receptacle and to enlarge the cut so made so that the receptacle will be mutilated beyond repair and use again as a container for liquids.

7. A cutter for producing a pouring opening in a receptacle and for mutilating the receptacle against subsequent use, comprising in combination, a wall having a rigidly disposed stationary cutting edge for cutting a pouring opening in a wall of a receptacle when the latter is forced against said cutting edge, and a cam wall adjacent the wall having said cutting edge for moving said receptacle laterally relative to said wall as the receptacle is forced against said cutting edge and thereby causing said stationary cutting edge to also cut into a wall of said receptacle adjacent the wall in which the pouring opening is produced for mutilating the receptacle beyond repair and use again as a container.

8. A cutter for producing a pouring opening in a receptacle and for mutilating the receptacle against subsequent use, comprising in combination, a one piece B shaped member having a body wall, a middle straight wall with a cutting edge terminating in a spear shaped cutting element for cutting an opening in a wall of a receptacle, curved side walls with cutting edges connecting said body wall with said middle wall for enlarging the opening produced in said receptacle and for turning back the cut away portions of said receptacle wall, and a cam wall formed on said body wall and projecting laterally therefrom in line with said middle wall for causing said spear shaped cutting element and said middle cutting edge to cut into a wall of said receptacle adjacent the wall in which the pouring opening was made and to enlarge the cut so produced to mutilate the receptacle beyond repair and use again as a container.

RUSSELL C. TAYLOR.
